CUSHIONING CRATE OR BOX LINER

William J. White, Portland, Oreg., assignor to
 Crown Zellerbach Corporation, San Francisco,
 Calif., a corporation of Nevada

Application April 12, 1937, Serial No. 136,416

1 Claim. (Cl. 217—3)

My invention relates particularly to cushioning liners usually employed for lining apple boxes, in order to enable the fruit to be packed firmly in the box while preventing it from becoming bruised in the box by impact in the handling and shipping of the box.

The liners heretofore used for this purpose are unsatisfactory because they are lacking in softness, flexibility and elasticity.

One of the principal objects of my invention is to provide an inexpensive cushioning box liner in the form of a packing strip of convenient length, both faces of which constitute similar soft cushion-like surfaces.

It is customary in packing apples to place a liner sheet at each side of the box, lapping the ends of the sheets over each other at the bottom of the box, and, after the box is packed, to lap the top ends of the liner sheet one over the other on top of the pack. Slats are then fastened to the top of the box over the pack and firmly pressed down with considerable force so as to insure a firm pack. In consequence, by the pressing and nailing down of the slats covering the top of the box, the liner sheet is firmly clamped between the top layer of apples and the overlying slats of the cover, as diagrammatically illustrated in Fig. 1a, setting up the restrained force in the direction of the arrow *m*. When the box is opened to render the apples accessible, or for inspection of the pack, the sudden release of the stress imposed on the upper ends of the liner sheets frequently causes the liner to split adjacent the side edge of the box, as diagrammatically illustrated by Fig. 2a, which represents, diagrammatically, a vertical transverse section of a box with the cover slats unfastened, thus releasing the force indicated by *m* and causing the liner—still firmly clamped between the upper layer of

apples and the overlying slats—to split under the stress imposed upon it, as indicated at *lx*. When this happens the appearance of the box is spoilt. There is also danger in the ordinary handling of the boxes before being opened that the liner will split along the edges of the sides of the box adjacent the bulging cover. A particular object of my invention is to provide a cushioning liner with ample inherent yield, accommodating such stresses, so that the liner sheet will not split as mentioned.

I attain these objects by making my cushioning liner of layers of thin sheets of paper crimped so as to have furrow-like pockers extending parallel in one direction, and by binding said layers together by means of narrow binder-strips

of paper of greater tensile strength than the sheets; said binder strips overlapping the sheets and being secured, and preferably cemented, to the edges of the outside sheets on both faces of the pad, said strips running transversely to the furrows of the crimps of said sheets. By such construction said binder strips hold the crimps in the sheets against spreading adjacent the binder strips, and thus maintain the pucker of said sheets, but at the same time leave the body 10 of the liner soft, flexible and elastic, so that the body of the liner may yield and spread transversely of the crimps and thus accommodate the stresses mentioned without splitting.

A further object of my invention is to provide 15 a cushioning liner of some thickness. This I accomplish by making an envelope, as it were, consisting of sheets of crimped paper, united at their edges by narrow binder-strips of greater tensile strength, as above described, and placing 20 in the envelope so produced one or more similar thin, crimped sheets. The pockers of the faces of the filler sheet co-acting with those of the sheets constituting the envelope serve to hold the filler sheets against lateral displacement. 25

The details of construction in my said cushioning elastic liner are hereinafter more fully described with further reference to the accompanying drawings, in which:

Fig. 1 is a diagrammatic view in perspective 30 of a short length of my liner;

Fig. 1a is a fragmentary longitudinal vertical section of a box of apples in which my liner is used;

Fig. 2 is a diagrammatic vertical longitudinal 35 section on the line 2—2 of Fig. 1;

Fig. 2a is a fragmentary vertical transverse section of the same box, but showing the cover slats unfastened from the box;

Fig. 3 is a diagrammatic vertical transverse 40 section on the line 3—3 of Fig. 1; and

Fig. 4 illustrates the crimped sheets and their binder strips separated in order to illustrate better the construction of my liner.

In the drawings, *a* and *b* indicate two sheets of 45 soft, creped paper which constitute the two identical soft faces of my liner, either face or surface of the liner being suitable for being placed in direct contact with the fruit. In many instances I have found it sufficient to make my liner merely 50 of two layers of creped paper. However, when greater cushioning effect is required, the number of layers may be increased as desired. The filler sheets are indicated by *c*. While filling, other than creped or crimped paper, may be 55

placed between the two outer sheets of crimped paper constituting the envelope of my filled liner, I do not consider this practical. According to my experience all the filler sheets or layers should 5 also be made of soft creped or crimped paper. It is important that the crimps or puckers *d* of all sheets should run parallel to each other and transversely to the length of my liner. The puckers of the soft filler sheets also function to 10 hold these sheets from slipping out from between the outer sheets of the liner.

The edging or binding strips *e* and *f* are folded over the edges of my liner and are secured in place by adhesive to the outer faces of my liner, 15 as above described and illustrated by Fig. 2. These binding strips are narrow so as to cover only a small margin at the edges of both faces of the liner and thus impose no restriction on the elasticity of the remaining portions of the creped 20 sheets. The binding strips extend transversely to the furrows or puckers, and, being of stronger, heavier paper, provide desired strength for my liner and, furthermore, prevent my liner from being stretched longitudinally to such extent as 25 to smooth out all the puckers or crimps. At the same time, since the binding strips cover only the edges of the soft crimped paper constituting the body of the liner, the uncovered surfaces remain flexible and elastic. My liner is 30 conveniently made up in any convenient width, and cut into desired lengths as used. If desired, it may be wound in rolls for shipment.

If desired, the creped paper constituting my liner may be impregnated with some preservative 35 such as is used for fruit wrappers. The narrow binder strips of heavy paper are suitable also for printing, coloring or other distinctive decoration.

The word "crimped" as used in the specification 40 is to be understood as designating any type of folds produced in the sheet extending in one direction, as for example, produced in the customary "creping" of a paper sheet.

As mentioned previously, Fig. 1a illustrates a sealed box of apples in which a liner is used. The liner, indicated by *o*, extends up next to the side *g* of the box and thence over on top of the fruit beneath the slats *h* which constitute the box cover. The cover slats *h* are secured to the top 5 of the end *g'* of the box by the nails *i*. When the cover slats *h* are pulled loose from the ends *g'* of the box, as illustrated in Fig. 2a, in the opening 10 of the box, the released pressure indicated by the arrow *m*, causes the fruit to push the cover slats and upper layer of the fruit upward, thus causing the liner *o*, which is held clamped between the slats and the fruit to be split along the top edge of the sides *g* of the box, as indicated 15 by the arrow *n*. With my liner, however, this could not occur, for the puckers in the crimped sheets permit the liner to stretch, with the result that neither face of the liner is split.

I claim:

A pack of the character described comprising a firm box-like body containing the pack and a resilient cover firmly fastened to the top of the sides of the body and exerting pressure on the pack, a flexible rectangular elongate cushion liner sheet enveloping the sides of the pack and extending beyond the tops of the sides of said body, said liner sheet made up of a plurality of superimposed sheets of softly crimped paper, the crimps of each of said sheets extending transversely to its length, and relatively narrow reinforcing binding strips firmly uniting said sheets along the edges of their long sides and retaining said crimps in said sheets, the ends of the liner sheet being lapped over each other and over the pack under said cover, whereby, when the cover is removed, the crimps of said sheets will permit the sheet to stretch lengthwise and thus yield to and accommodate without being ruptured the reflex strain imposed upon said lapped ends of 40 the liner sheet by the sudden release of the pressure of said cover on the pack.

WILLIAM J. WHITE.
